UNITED STATES PATENT OFFICE

165,743

MEASURING DEVICE FOR SEMISOLIDS

Otto Dieckmann, Cincinnati, Ohio

Application September 28, 1949, Serial No. 5,199

Term of patent 3½ years

(Cl. D52—1)

To all whom it may concern:

Be it known that I, Otto Dieckmann, a citizen of the United States, residing at Cincinnati, in the county of Hamilton and State of Ohio, have invented a new, original, and ornamental Design for a Measuring Device for Semisolids, of which the following is a specification, reference being had to the accompanying drawing, forming part thereof.

The figure is a perspective view of a measuring device for semisolids, showing my new design.

I claim:

The ornamental design for a measuring device for semisolids, as shown.

OTTO DIECKMANN.
